UNITED STATES PATENT OFFICE.

JOHN C. BECK, OF MILTON, INDIANA, ASSIGNOR TO THE DIDDIDGE-BECK CO., OF MILTON, INDIANA, A CORPORATION OF INDIANA.

CANOPY DEVICE FOR BURIAL-CASKETS.

1,270,773.

Specification of Letters Patent.

Patented July 2, 1918.

Application filed November 18, 1916. Serial No. 132,038.

To all whom it may concern:

Be it known that I, JOHN C. BECK, a citizen of the United States, residing in the town of Milton, in the county of Wayne, 5 State of Indiana, have invented a new and useful Canopy Device for Burial-Caskets, of which the following is a full, clear, and comprehensive specification and exposition, the same being such as will enable others to 10 make and use the same with exactitude.

The object of this invention, broadly speaking, is to provide a canopy device for burial caskets or the like which will be strong and durable in construction, neat and attractive in appearance, easily attached and detached with relation to a casket, which 15 will be economical in use and effective in practice, and which can be manufactured and sold at a comparatively low price.

20 The particular object of the invention is to provide an adjustable, collapsible and detachable canopy device for burial caskets, the same being adapted to be attached to the open lid of a casket and adapted to form a support for a fabric canopy to be placed thereover and to hang down around the casket to protect the corpsa which may be contained in the casket, and to add an artistic appearance to the entire *ensemble*.

25 Other minor objects and particular advantages of the invention will suggest themselves in the course of the following description and that which is new and useful will be correlated in the claim.

30 The preferred means for carrying out my invention in a practical manner is shown in the accompanying drawings, in which—Figure 1 is a perspective view of my complete device in operative position in connection with a burial casket. Fig. 2 is a plan view of my device in connection with the lid of a burial casket. Fig. 3 is a plan view of the main portion of my device collapsed or in folded condition. Fig. 4 is a detail vertical section, as taken centrally through the rear portion of one of the side arms and the upper or forward portion of the lid, but taken on a larger scale, and with the fabric omitted. And Fig. 5 is an end elevation of 45 one of the outwardly extending side arms of the device.

Similar indices denote like parts throughout the several views.

In order that the construction, the operation, and the advantages of my invention

may be better understood and appreciated I will now take up a detailed description thereof in which I will set forth the invention as briefly and as comprehensively as I may.

60 In the drawings I have shown an ordinary burial casket, in which letter A denotes the body of the casket and B denotes the lid thereof, which lid is hinged to said body.

The invention proper comprises four extensible arms, which are hinged together and adapted to be detachably connected to the upper corners of the opened lid, as herein set forth.

65 The two end or side arms are identical with each other, and they comprise the inner members 1 and 2, right and left respectively, and the respective outer members 3 and 4.

The central portions of the members 1 and 3 overlap each other and they are halved together, and they are retained in sliding contact with each other by the clips 5 and 6, the former being secured to the member 3 and it extends around the member 1, while the latter is secured to the member 1 and extends around the member 3, thereby providing a slidable and extensible joint.

70 The central portions of the members 2 and 4 also overlap each other and they are halved together and they are retained in sliding contact with each other by the clips 7 and 8, the former being secured to the member 4 and it extends around the member 2, while the latter is secured to the member 2 and extends around the member 4, thereby 75 providing a slidable and extensible joint.

80 Formed integral with the lower edge of the inner ends of the members 1 and 2 are the respective brackets 9 and 10 whose larger ends are flush with the respective members 1 and 2.

85 Formed in the inner ends of the members 1 and 2, and extending down into the ends of the members 9 and 10, are the respective elongated vertical cavities 11 and 12.

90 Numerals 13 and 14 denote right-angular corner-plates, which cover the inner ends of the respective members 1 and 2, being set flush with the ends of the respective brackets 9 and 10, and they extend outward on the upper edge of the respective members 1 and 2, they being secured in place by screws or the like as shown. Extending upward through the lower edge portion of the center of the corner-plates 13 and 14 are inverted 100

U-shaped slots, as indicated at α in Fig. 5, which slots are of less width than are the cavities 11 and 12.

Round headed screws 15 and 16 are inserted in the contact face of each of the upper corners of the lid D, and in such position that they will lie horizontal when the lid D is opened or in vertical position, and the flat under faces of the heads of said screws are spaced from the contact face of the lid, which spaces are substantially equal to the thickness of the corner-plates 13 and 14.

Cavities 17' and 18' are formed in the contact face of the body A into which the heads of said screws may enter when the lid is closed, in order that the contact faces of the body and the lid may contact with each other and make a close joint.

In practice the members 1 and 2 are brought to such position that the heads of the screws 15 and 16 will enter the lower portions of the respective cavities 11 and 12, then the members 1 and 2 are moved downward which will cause the heads of said screws to move up into the upper portions of said cavities, thereby causing the portions of the plates 13 and 14 which form the sides of the slots α to engage under the heads of said screws, thereby locking the members 1 and 2 in such way that they will be supported extending out horizontally from the lid, as shown in Figs. 1, 2 and 4, yet permitting the members 1 and 2 to be easily removed when they are moved first upward and then forward.

The two front arms are identical with each other, and they comprise the two outer members 17 and 18, right and left respectively, and the respective central members 19 and 20.

The central portions of the members 17 and 19 overlap each other and they are halved together, and they are retained in sliding contact with each other by the clips 21 and 22, the former being secured to the member 19 and it extends around the member 17, while the latter is secured to the member 17 and extends around the member 19, thereby providing a sliding and extensible joint.

The central portions of the members 18 and 20 also overlap each other and they are halved together and they are retained in sliding contact with each other by the clips 23 and 24, the former being secured to the member 20 and it extends around the member 18, while the latter is secured to the member 18 and extends around the member 20, thereby providing a slideable and extensible joint.

The abutting ends of the members 19 and 20 are connected by the hinge 25 which is attached to the outer faces thereof as shown.

The outer end portion of member 17 con-

tacts with the end of the member 3, and they are connected by the hinge 26, which is attached to the inner faces thereof, substantially as shown.

The outer end portion of member 18 contacts with the end of the member 4, and they are connected by the hinge 27, as shown.

The members 19 and 20 are adapted to be locked in extended position by one or more hooks 28.

The members 1 and 3 are adapted to be locked together in adjusted position by the thumb-screw 29; in like manner the members 17 and 19 are adapted to be locked together by the thumb-screw 30; likewise the members 18 and 20 are adapted to be locked together by the thumb-screw 31; and the members 2 and 4 are adapted to be locked together by the thumb-screw 32.

Extending up from the horizontal portion of each of the corner-plates 13 and 14 is a knob or button, as the knobs 33 and 34, respectively.

Numeral 35 denotes a comparatively heavy elastic strip, which extends across between the members 1 and 2, and in each end portion thereof is a socket cap, 36 and 37, which are adapted to clamp over the respective knobs 33 and 34 to hold the strip 35 in extended position as shown. Gauze or other fabric 38 is secured along the entire length of the strip 35, and it should extend out over all of the members of the arms which form the frame, and it should hang down around the body of the casket as desired.

From the above it will be observed that the main frame of the device may be collapsed and folded into a small compass of space, as in Fig. 3, and then when desired to be used it may be opened out as in Fig. 105 2 and the length and the width thereof may be adjusted to the size of the casket on which it is to be used.

In order to adapt the casket to receive the device one has only to insert the screws 15 110 and 16, as in Fig. 4, and then suspend the frame from said screws as previously stated.

From the above it is apparent that the device may be adjusted to various sizes of caskets, and that it may be attached or removed with very little trouble, as the device does not necessarily form an integral part of the casket, but is simply an attachment therefor.

I desire that it be understood that various 120 changes may be made in the several details of construction and adaptation without departing from the spirit or sacrificing any of the advantages of the invention.

Having now fully shown and described 125 my invention, what I claim and desire to secure by Letters Patent of the United States, is

In combination with a burial casket having a lid adapted to stand in vertical posi-

tion when open, a canopy device comprising a frame composed of extensible side-arms and an extensible front arm hinged at its ends to the outer ends of the side-arms, a hinge connecting the two halves of the front arm whereby the front arm is made foldable, brackets carried by the inner ends of the side arms and each having a cavity in its face adjoining the lid, a right angular corner plate covering the inner end of each of the side arms and extending over a portion of the respective cavities above mentioned, there being an inverted U-shaped slot extending upward through the lower edge portion of the center of each of said corner plates, and a screw inserted in the contact face of the upper corners of the lid with their heads adapted to enter the respective

cavities mentioned and to engage the respective corner plates to detachably lock the device in extended position in connection with the lid, a length of elastic detachably connecting the rear ends of the side arms, and a fabric canopy attached to the elastic and adapted to extend out over the frame formed by the side arms and the front arm and to extend down around the body of the casket, all substantially as shown.

In testimony whereof I have hereunto subscribed my name to this specification in the presence of two subscribing witnesses.

JOHN C. BECK.
